AUGUST SUNDH, OF HASTINGS-UPON-HUDSON, NEW YORK.

GATE-HINGE.

1,139,822.

Specification of Letters Patent. Patented May 18, 1915.

Application filed January 11, 1915. Serial No. 1,527.

To all whom it may concern:

Be it known that I, AUGUST SUNDH, a citizen of the United States, residing in Hastings-upon-Hudson, in the county of 5 Westchester and State of New York, have invented a new and useful Improvement in Gate-Hinges, of which the following is a specification.

My invention relates to gate hinge mechanism, and has for its principal objects the provision of a hinge which will center the gate and keep the same centered; also a hinge which will carry very heavy loads with the minimum of wear; a hinge which 10 is self lubricating at all times; a hinge in which the swing of the gate back and forth by central position after having been operated is reduced to a minimum, and a hinge in which the parts are well protected 15 from the elements.

With these and other objects in view, I have devised an apparatus which is fully set forth in detail in the accompanying drawings.

Referring now to the drawings, Figure 1 is a sectional elevational view showing my device applied to a gate and gatepost with the parts in central position; Fig. 2 is a sectional plan view taken on the line *a—a* 20 of Fig. 1; Fig. 3 is a sectional plan view of part of Fig. 1 taken on line *b—b*; Fig. 4 is a sectional plan view on the line *d—d* of Fig. 1; Fig. 5 is a sectional plan view on the line *e—e* of Fig. 1; Fig. 6 is a part 25 sectional elevation view showing the position taken by the hinge when the gate is opened in one direction; Fig. 7 shows in sectional elevation the hinge with gate opened in the opposite direction.

Referring to the drawings in detail, my hinge comprises two telescoping parts or cups, 1 and 2, in this instance the part 1, being attached to the gate, and part, 2, to the gate post, it being understood, however, 40 that their location may be reversed. The part, 1, has a lateral extension, 3, substantially rectangular in cross section, the outer face of which is concaved to fit nicely the face of the gate to which it is to be attached. To secure the hinge to the gate, I have provided a clamp, 4, having its face concaved to fit the face of the gate. These clamping members are secured to the gate 45 by means of bolts, 5, one on each side of the face of the gate. I have shown the part, 2, formed with an extension similar

to that on part, 1, which extension is secured to the gate post in the same way as the extension, 3, is secured to the gate. The inside of the part 2 is cylindrical in shape, 60 nearly to the bottom, where the cylinder is reduced in diameter, forming a shoulder, 6, on the inside of the cylinder, near the bottom. Resting on this shoulder, 6, is a ring, 7, slightly smaller in diameter than 65 the inside of the part, 2. Formed on the bottom of this ring is a downwardly extending projection, 8, a clearance being left between the end of this extension and the bottom of the cylinder. Formed in this 70 extension is a port, 9, which passes up through the extension and through the ring, 7. This port is of a shape to permit a ball valve, 10, to be retained therein. This portion of the port extends up to 75 about midway of the depth of the ring, the rest of the port being very much enlarged.

Formed on the inside of the cylinder, 2, and extending longitudinally of it from 80 about midway of its length to the shoulder, 6, are ribs, 11, (see Fig. 4), two in number, set diametrically opposite each other.

Spaced at equal distances around the periphery of the cylinder 2, and on the 85 inside, are cut four grooves, 12, for a purpose hereinafter pointed out; and spaced between two sets of these grooves, 12, and diametrically opposite each other are two more grooves, 13. All these grooves extend 90 longitudinally of the cylinder from about midway the length of the cylinder to the shoulder 6. Mounted in the cylinder, 2, is a spindle, 14, fitted in Babbitt metal 95 bearings, or some other antifriction metal bearings, the spindle fitting rather loosely. This spindle, 14, has cut therein very coarse threads, the lower half of the spindle having a plurality of left hand threads and the upper half a plurality of right 100 hand threads.

I have in practice found it very desirable to have a plurality of threads on the spindle in order to get sufficient bearing surface and at the same time have a sufficient depth of pitch. The antifriction metal bearings for the spindle is securely held in place as will be explained more in detail later on.

Formed on the spindle 14, at about its 110 middle, is a collar, 16, the diameter of which is large enough to permit the collar

to span a little more than the distance between the ribs 11. The length of the ribs 11, and the position of the collar, 16, on the spindle, 14, are such that when the end 5 of the spindle rests on the ring, 7, the collar, 16, will rest on the top of the ribs, 11. The grooves, 13, are formed wedge shaped, that is smaller at the bottom than at the top, which prevents the babbitt from being 10 pulled out of the cylinder, 2. The upper half of the spindle, 14, carries the upper cylinder, 1. This cylinder is slightly larger in diameter than the lower part, 2.

Formed within the cylinder, 1, is a concentric cylinder, 17, having two grooves, 18 therein, set diametrically opposite each other. These grooves are wedge shaped, being larger at the bottom than at the top, being so formed to retain the antifriction 20 metal bearing 19 in place, said bearing being screw threaded to accommodate the spindle, 14. The length of the cylinder, 17, is such that when the collar, 16, is resting on the ribs, 11, the end of the cylinder, 17, rests on the upper side of the collar, 16, and the top of the spindle does not quite touch the inside of the bottom of the cylinder, 17.

Extending down through the center of 30 the spindle is a small opening, 20, which extends down until it meets an opening 21, let into the collar, 16 at right angles to the opening, 20. This opening 21, is screw-threaded to receive a hollow plug 22, carrying 35 a ball valve 23. Formed within this plug is a shoulder 24 smaller in diameter than the diameter of the ball, 23. In assembling this valve, the ball is dropped into the plug from the inner end and then the 40 end of the plug struck a slight blow enough to close the opening sufficiently to retain the ball within the plug. The shoulder, 24, prevents the ball escaping through the other end of the plug. The ball valve in the lower 45 part of the hinge is assembled in the same way. In this case the lower part of the port, 9, being smaller in diameter than the ball, 10, the ball is dropped in to the port from the top and then the top is partially 50 closed the same as just pointed out in connection with the upper ball valve.

The method of assembling the hinge is as follows: The ring, 7, is provided with cut out portions 25, setting diametrically opposite each other in the outer periphery of the ring, and corresponding in shape to the ribs 11 formed on the walls of the cylinder 2. The ring is placed in the cylinder with its cut out parts, 25, registering with the ribs, 60 11, and dropped down into the cylinder until it rests on the shoulder 6. Also in the periphery of the ring, 7, are provided cut out portions, 12', four in number, located so as to register with the openings or 65 grooves, 12, on the inner wall of the cylin-

der 2, when the ring is in place. I also provide cut out portions, 13', in the periphery of the ring, which register with the lower portion of the grooves, 13, in the wall of the cylinder, 2, when the ring is in place. With 70 the ring in place with its various grooves registering with the grooves in the walls of the cylinder, 2, I next drop down on to the ring a false spindle threaded as is the spindle, 14, but slightly larger in diameter than 75 said spindle. Next wooden plugs or plugs of any suitable material shaped as are the several openings or grooves down the side of the cylinder, 2, and in the ring, 7, are driven into the several openings just mentioned. Babbitt metal in a molten state is then poured into the opening or space around the spindle completely filling the space and also filling the space between the threads. The plugs, it should be noted, are 80 not to be driven into the grooves 13, but only in the grooves 12 and cut out portions 12', registering therewith. The babbitt will therefore fill up the grooves 13 and 13' registering therewith. It will thus be seen 85 that when the false spindle is screwed out the Babbitt metal will be left in place screw threaded to form a bearing for the true spindle 14. The grooves 13, and 13', will 90 prevent the babbitt from being pulled out, being wedge shaped, and also hold the ring, 7, firmly in the one position. The babbitt in the upper part of the hinge is put in much 95 the same way, in this case the wedge shaped grooves, 18, holding the babbitt from being pulled out. The plugs are then knocked 100 out, leaving four grooves, 12, extending up the side of the babbitt on its outer periphery in the lower part of the hinge. The cup 2 is then partially filled with lubricant, and the 105 spindle, 14, screwed down into the lower bearing until it rests on the collar 7; at that time the collar 16 will rest on the shoulder or ribs, 11. The upper part of the hinge is then screwed down on to the spindle, 14, the 110 relative lengths of all the parts being such that when the lower end of the cylinder 17 rests on the collar 16, there will be a slight clearance between the upper part of the spindle, or upper end of the spindle, 14, and the inside of the bottom of the cylinder 17, and a slight clearance between the top of 115 the part 2 and the bottom of the part 1. A clearance is allowed between the parts 17 and 2.

In operation, suppose the gate is opened as shown in Fig. 6; in this case, the tendency of the spindle is to screw down into its bearing, but by reason of the collar 16 resting on the ribs 11 it is held from moving longitudinally and the upper part of the hinge will therefore travel up the upper part of the spindle as shown in Fig. 6, at the same time the lubricant will be drawn into the port 21 and will flow up through the 120 125 130

opening 20, up into the space which will then be present between the top of the spindle and the bottom of the cylinder 17. When the gate is released it will return to its central position by its own weight, being heavy enough to travel down the threads of the spindle and at the same time by reason of the said threads returning to closed position. By reason of the ball valve 23 the oil 5 which was in the chamber above the upper end of the spindle cannot escape through the port, 21, and it will therefore be forced down through the threads of the spindle lubricating the threads of the spindle 10 thoroughly. In addition to this forced lubrication, my arrangement has the advantage of slightly retarding the closure 15 of the gate, which is a great advantage. When opening the gate in the opposite 20 direction, the tendency of the upper part of the hinge is to screw down on to the spindle, but is prevented from so doing by reason of the cylinder 17 contacting with the collar 16. The whole spindle will have 25 to turn therefore and be drawn partially out of its bearing, that is its lower bearing. This will suck oil up through the port 9 into the chamber which will then be present at the bottom of the spindle. When the 30 gate is released and closes the oil will be prevented from escaping through the port 9 by reason of the ball 10 and it will therefore be forced up through the threads of the spindle, thoroughly lubricating them. 35 The retarding effect of the oil will be present in this instance as in the case of opening the gate in the opposite direction, as is obvious.

It will thus be seen that I have provided 40 a very simple efficient hinge, and one which will always be thoroughly lubricated. The fact that the gate is lifted bodily each time it swings past closed position is an excellent feature, as it, to a great extent, does away 45 with the swinging back and forth of the gate under its own momentum as is the great trouble with hinges at present in use. In addition to that, I have the retarding effect of the oil to cut down the momentum of the 50 gate in closing. I only leave a small space between the top of the part 2 and the inside of the part 1, which together with the telescoping nature of the two parts quite efficiently keeps out dirt from the inside of the 55 hinge.

It is to be understood that those skilled in the art may make various changes in the details of construction and arrangement of parts herein shown, without departing from 60 the spirit and scope of my invention, I desire therefore not to be limited to the precise construction shown.

What I claim, and desire to secure by Letters Patent of the United States is:—

65 1. A gate hinge, comprising a stationary

member and a manually operable member, screw threads in said members, and a screw with right and left hand threads coacting with said members.

2. A gate hinge comprising a stationary 70 member and a manually operable member with telescoping inclosures, screw threads in said members, a screw with right hand threads on one end and left hand threads on the other, coacting with said members. 75

3. A gate hinge, comprising one stationary member and one manually operable member, said members having screw threads, a screw threaded member fitting in said threads, a central projection on said last 80 named member adapted to maintain the members at rest.

4. A gate hinge, comprising one stationary member and one manually operable member, multiple screw threads in said 85 members, one member having multiple right hand screw threads, and one member having multiple left hand screw threads, and a multiple screw threaded member fitting the multiple threads of said members. 90

5. A gate hinge, comprising members, one adapted to be held stationary and adapted to carry the load, the other adapted to be manually operated, screw threads in said members, a screw for said screw threads coacting with said members, and means to force lubricant between the threads of the screw and the threads of the members. 95

6. A gate hinge, comprising a plurality of members and adapted to carry a load, one member being stationary and one member adapted to be manually operated to either side from center, screw threads in said members, a screw fitting said screw threads, said threads in the members and threads of the 100 screw adapted to raise the manually operated member in a vertical direction when the same is swung from center and also adapted to return the said member to a central position from one side or the other by gravity. 110

7. A gate hinge comprising a plurality of coöperating mechanical parts, two of said parts provided with screw threads, one of said parts having threads fitting the threads in said two members, and antifriction metal 115 forming the threads in said two members, and lubricating means for said antifriction metal threads.

8. A gate hinge comprising a plurality of coöperating parts, two of the parts having 120 screw threads, a third part having screw threads to fit the threads of the first said two parts, means embodied with the two first parts to contain a lubricant, one of said first two parts being adapted to be raised and lowered and thereby operate the lubricant, and means to retard the lubricant when said first part is lowered, and thereby obtain a retarding effect on said part when the same is being lowered. 125 130

9. A gate hinge comprising a plurality of coöperating parts, two of the parts having screw threads, a third part having screw threads to fit the threads of the first two parts, means embodied with the first two parts to contain lubricant, one of said first two parts being adapted to be raised and lowered and to thereby operate the lubricant, and means coöperating with the first two parts to force lubricant through and around the same when being lowered.

10. A gate hinge comprising a plurality of members of which members the one is stationary and one is adapted to be raised and lowered in a vertical direction, screw threads in said members consisting of anti-

friction metal molded in the said two members, a screw combining said two members and adapted to raise and lower one member in a vertical direction when the same is swung from one side or the other from a center, and means embodied in said two members to hold the anti-friction metal permanently in place both from twisting and pulling out from said members.

20
25
In testimony whereof, I have signed my name to this specification in the presence of two subscribing witnesses.

AUGUST SUNDH.
